ROTARY EXPANSIBLE DESCALER FOR
BOILER TUBES AND THE LIKE

Virgil H. Baker and Carl M. Anderson, Springfield, Ohio, assignors to Elliott Company, Jeannette, Pa., a corporation of Pennsylvania

Application July 29, 1947, Serial No. 764,456

6 Claims. (Cl. 15—104.13)

1

This invention relates to expanding tools or heads for cleaning tubes, and more particularly to power driven heads especially suitable for cleaning security circulators and thermic siphons in railroad locomotives.

It is among the objects of this invention to provide such an expanding cleaner head which is short and compact, which has a simple and rugged construction, which is relatively inexpensive to make, and which can expand from a small diameter to a comparatively large size.

In accordance with this invention, each of a plurality of parallel spacing members is in the form of a channel which is substantially V-shape in cross section. These members are rigidly connected in such a manner as to be supported in a circle with their apex edges pointed toward the axis of the circle. The channels are spaced equal distances apart to form between them slots which have parallel side walls formed by the sides of the channels. The walls are provided with transverse holes through their rear ends. An arm normally lies in each of the slots and has a passage through its rear end in which there is a pivot pin that projects into the adjacent wall holes. The pins are held in place most suitably by prongs projecting forward into the channels from a retaining member at their rear ends. The rear end of the head is adapted to be connected to driving means for rotating the head to swing the arms out of the slots. A spider is slidably disposed in the slots and is pivotally connected by links to the front end portions of the arms in order to link the arms together so that all must swing together and the same distance. Cutting members, such as toothed wheels or rollers, are rotatably mounted on the front ends of the arms. The links preferably are connected to the spider by pivot pins which are held in place by the side walls of the slots. When the arms are collapsed, the links extend forward along the arms and have their front ends connected to the arms by pivot pins which preferably have reduced end portions that project into holes in the links. With this construction the links, which are prevented by the side walls of the slots from spreading apart, prevent the pivot pins at their front ends from slipping out of the arms. The distance that the arms can swing outward can be limited by their rear ends striking an obstruction, such as a connecting member that unites the channels.

The preferred embodiment of the invention is illustrated in the accompanying drawings in which Fig. 1 is a view of the cleaning head collapsed; Figs. 2 and 3 are transverse sections taken on the lines II—II and III—III, respec-

tively, of Fig. 1; Fig. 4 is a side view of the fully expanded head, but with the lower half shown in section, and Fig. 5 is a fragmentary cross section of an arm taken on the line V—V of Fig. 4.

Referring to the drawings, four metal channels 1, each of which forms a right angle in cross section, are arranged in a circle with their inner or apex edges pointing toward the axis of the circle. The channels are spaced equal distances apart to form between them slots 2 which have parallel side walls formed by the sides of the channels. The channels are held rigidly in this position by means of a connecting member which, preferably, is a solid metal block 3 integral with the rear end apex portions of the channel as shown in Figs. 3 and 4. Integral with the block is a threaded stud 4 which projects rearward for a purpose to be described presently.

Lying in each slot 2, when the head is collapsed, is an arm 6 that projects from the front end of the slot. There is a passage through the rear end of each arm, and a pivot pin 7 extends through the passage and has its ends projecting into holes through the rear ends of the adjoining channel walls. To keep the pins from slipping out of place, a retaining member is employed which has a disc-like body 8 engaging the rear ends of the channels 1 and block 3 and having a central opening through which the threaded stud 4 extends. This body is provided with forwardly extending prongs 9 which slide into the rear end portions of the channels and overlie the ends of pivot pins 7 to lock them in place. The retaining member is held in place by a coupling sleeve 11 screwed onto stud 4. The rear end of the coupling is adapted to be connected to the drive shaft of a motor (not shown) which rapidly rotates the head and thereby, through centrifugal force, causes the front ends of the arms 40 to swing outward.

In order that the head will clean the tubular member in which it is disposed, the front end of each arm 6 is provided with a rearwardly extending bore in which a headed pin 12 is inserted. Rotatable on the projecting portion of the pin is a toothed cutting wheel 13 of conventional form. When the arms are collapsed in slots 2, the headed pins converge forward as shown in Fig. 1, so that the cutting wheels will not project radially beyond the periphery of the rest of the head.

When this cleaning head is used in a thermic siphon which is provided with a longitudinal slot through its wall, it is necessary to keep arms 6 from flying out through the slot as the head ro-

states. This is accomplished by linking all of the arms together so that they all must swing out and in unison; the greatest distance that any arm can swing away from the axis of the head thereby being limited by the maximum distance that any other arm can swing away from the axis. In accordance with this invention, the tying together of the arms is done partly by means of a cross-shape block or spider 16 slidably disposed between channels 1. The parts of the spider that project into slots 2 are considerably narrower than the slots to permit the rear ends of pairs of links 17 to be interposed between the sides of the spider and the channels. The spider has passages therethrough in which are disposed pivot pins 18 that project into holes in the adjoining links. These pins are held in place by the channel walls at their ends as shown in Fig. 2. The pins 18, spider, and links are assembled and then slipped into the front ends of the slots before the rear ends of arms 6 are attached to the channels.

The inner surfaces of the arms are provided with recesses 20 that accommodate the spider when it is in its rearward position, indicated by broken lines in Fig. 4, adjacent the connecting block 3. The sides of the arms are provided with recesses 21 along which links 17 extend when the arms are collapsed in the slots. The front ends of the links are connected to the arms in front of the channels by means of pivot pins 22. Each pin extends through a passage in an arm and, as shown in Fig. 5, has projecting end portions of reduced diameter that extend through holes in the adjoining ends of the links. As each pair of links is prevented by the side walls of a slot 2 from spreading apart, the front ends of the links keep their pivot pin 22 from slipping out of the adjoining arm. Of course, the links are slipped over the ends of this pin before the spider is inserted in the slots. Pin 22 also extends through a notch in the side of the adjoining headed pin 12 to lock the latter in the arm.

To prevent the front ends of arms 6 from swinging so far out of the slots that the adjoining links pull the spider either out of the slots, or into a position in which it will be aligned with the links so that the assembly will act like a straightened toggle that would prevent the arms from collapsing, the expansion of the arms is limited. This is accomplished by providing the rear ends of the arms behind pins 7 with surfaces 23 that swing inward as the front ends of the arms swing outward. These surfaces will strike the connecting block 3 and stop the outward movement of the arms before the spider can be pulled forward into a locking position.

It will be seen that this cleaning head is relatively short and compact because nothing extends ahead of the headed pins on which the cutting wheels are mounted. The spider is surrounded by the arms and channels in a well protected position. It will be noticed in particular that none of the parts of this head are riveted together, and that the only threaded member is the stud that receives the coupling by which the head is connected to the driving motor. Consequently, the cost of assembling the head is reduced. The head also can be quickly disassembled for repair by merely unscrewing the coupling so that the retaining member can be removed. The various pivot pins then can be pushed out of position so that the different element will come apart. By not having to use rivets, pivot pins of larger diameter can be employed, thereby increasing the

strength of the connections. The cleaner head disclosed herein can be made of such a size that when collapsed, it can pass through an opening of $2\frac{1}{8}$ inches diameter, and then expand sufficiently to clean the inside of a tube of 7 inch diameter. This is necessary for cleaning thermic siphons.

According to the provisions of the patent statutes, we have explained the principle and 10 construction of our invention and have illustrated and described what we now consider to represent its best embodiment. However, we desire to have it understood that, within the scope of the 15 appended claims, the invention may be practiced otherwise than as specifically illustrated and described.

We claim:

1. All expanding head for cleaning tubes and 20 the like, comprising a plurality of parallel spacing members, each member being in the form of a channel substantially V-shape in cross section, means rigidly connecting said members to support them in a circle with their apex edges pointing toward the axis of the circle and their sides spaced 25 apart to form slots between them having parallel side walls provided with transverse holes through their rear ends, and arm normally lying in each of said slots and having a passage through its rear end, a pivot pin disposed in said passage and 30 projecting into the adjacent wall holes, the rear end of the head being adapted to be connected to driving means for rotating the head to swing the arms out of the slots, a spider slidably disposed in said slots, the opposite sides of each 35 arm being provided with recesses, links normally lying in said recesses with their front ends pivotally connected to the arms and their rear ends pivotally connected to the spider to link the arms together so that all of them must swing in 40 unison, and cutting members rotatably mounted on the front ends of the arms.

2. An expanding head for cleaning tubes and 45 the like, comprising a plurality of parallel spacing members, each member being in the form of a channel substantially V-shape in cross section, means rigidly connecting said members to support them in a circle with their apex edges pointing toward the axis of the circle and their sides spaced 50 apart to form slots between them having parallel side walls provided with transverse holes through their rear ends, an arm normally lying in each of said slots and having a passage through its rear end, a pivot pin disposed in said passage and 55 projecting into the adjacent wall holes, the rear end of the head being adapted to be connected to driving means for rotating the head to swing the arms out of the slots, a spider slidably disposed in said slots, links pivotally connected to the front end portions of the arms and extending 60 rearward to the spider, pivot pins connecting the links to the spider and being substantially as long as the width of said slots so that said last-mentioned pivot pins are held in place by said side walls, and cutting members mounted on the front 65 ends of the arms.

3. An expanding head for cleaning tubes and 70 the like, comprising a plurality of parallel spacing members, each member being in the form of a channel substantially V-shape in cross section, means rigidly connecting said members to support them in a circle with their apex edges pointing toward the axis of the circle and their sides spaced 75 apart to form slots between them having parallel side walls provided with transverse holes through their rear ends, an arm normally lying

in each of said slots and having a passage through its rear end, a pivot pin disposed in said passage and projecting into the adjacent wall holes, the rear end of the head being adapted to be connected to driving means for rotating the head to swing the arms out of the slots, a spider slidably disposed in said slots, pairs of parallel links engaging the spider and spacing it from said side walls, a pivot pin connecting the rear end of each pair of links to the spider and being substantially as long as the width of the slot in which it is disposed so that the pin is held in place by said side walls, means pivotally connecting the front end of each pair of links to an arm, and cutting members mounted on the front ends of the arms.

4. An expanding head for cleaning tubes and the like, comprising a plurality of parallel spacing members, each member being in the form of a channel substantially V-shape in cross section, means rigidly connecting said members to support them in a circle with their apex edges pointing toward the axis of the circle and their sides spaced apart to form slots between them having parallel side walls provided with transverse holes through their rear ends, an arm normally lying in each of said slots and having a passage through its rear end, a pivot pin disposed in said passage and projecting into the adjacent wall holes, the rear end of the head being adapted to be connected to driving means for rotating the head to swing the arms out of the slots, a spider slidably disposed in said slots, pairs of parallel links engaging the spider and spacing it from said side walls, a pivot pin connecting the rear end of each pair of links to the spider and being substantially as long as the width of the slot in which it is disposed so that the pin is held in place by said side walls, the front ends of the links being provided with holes therethrough, a pivot pin loosely mounted in each arm and having ends of reduced diameter projecting into said holes in the adjoining pair of links, the width of said slots being such that their side walls substantially engage the links to keep each pair of parallel links from moving away from the arm between them, and cutting members rotatably mounted on the front ends of the arms.

5. An expanding head for cleaning tubes and the like, comprising a plurality of parallel spacing members, each member being in the form of a channel substantially V-shape in cross section, means rigidly connecting said members at their rear ends to support them in a circle with their apex edges pointing toward the axis of the circle and their sides spaced apart to form slots between them having parallel side walls provided

with transverse holes through their rear ends, an arm normally lying in each of said slots and having a passage through its rear end, a pivot pin disposed in said passage and projecting into the adjacent wall holes, means at the rear ends of said channels adapted to connect the head to driving means for rotating it to swing the arms out of the slots, a spider slidably disposed in said slots in front of said first-mentioned connecting means, links pivotally connecting the spider to the front end portions of the arms to link the arms together so that all must swing in unison, and cutting members mounted on the front ends of the arms.

15. An expanding head for cleaning tubes and the like, comprising a plurality of parallel spacing members, each member being in the form of a channel substantially V-shape in cross section, means rigidly connecting the rear ends of said members to support them in a circle with their apex edges pointing toward the axis of the circle and their sides spaced apart to form slots between them having parallel side walls provided with transverse holes through their rear ends, an arm normally lying in each of said slots and having a passage through its rear end, a pivot pin disposed in said passage and projecting into the adjacent wall holes, the rear end of the head being adapted to be connected to driving means for rotating the head to swing the arms out of the slots, a spider slidably disposed in said slots in front of said first-mentioned connecting means, links pivotally connected to the spider and extending forward along the sides of the arms 20 in the slots, means pivotally connecting the front ends of the links to the arms so that all arms must swing in unison, and cutting members rotatably mounted on the front ends of the arms.

25. An expanding head for cleaning tubes and the like, comprising a plurality of parallel spacing members, each member being in the form of a channel substantially V-shape in cross section, means rigidly connecting the rear ends of said members to support them in a circle with their apex edges pointing toward the axis of the circle and their sides spaced apart to form slots between them having parallel side walls provided with transverse holes through their rear ends, an arm normally lying in each of said slots and having a passage through its rear end, a pivot pin disposed in said passage and projecting into the adjacent wall holes, the rear end of the head being adapted to be connected to driving means for rotating the head to swing the arms out of the slots, a spider slidably disposed in said slots in front of said first-mentioned connecting means, links pivotally connected to the spider and extending forward along the sides of the arms 30 in the slots, means pivotally connecting the front ends of the links to the arms so that all arms must swing in unison, and cutting members rotatably mounted on the front ends of the arms.

35. An expanding head for cleaning tubes and the like, comprising a plurality of parallel spacing members, each member being in the form of a channel substantially V-shape in cross section, means rigidly connecting the rear ends of said members to support them in a circle with their apex edges pointing toward the axis of the circle and their sides spaced apart to form slots between them having parallel side walls provided with transverse holes through their rear ends, an arm normally lying in each of said slots and having a passage through its rear end, a pivot pin disposed in said passage and projecting into the adjacent wall holes, the rear end of the head being adapted to be connected to driving means for rotating the head to swing the arms out of the slots, a spider slidably disposed in said slots in front of said first-mentioned connecting means, links pivotally connected to the spider and extending forward along the sides of the arms 40 in the slots, means pivotally connecting the front ends of the links to the arms so that all arms must swing in unison, and cutting members rotatably mounted on the front ends of the arms.

Certificate of Correction

March 14, 1950

VIRGIL H. BAKER ET AL.

It is hereby certified that errors appear in the printed specification of the above numbered patent requiring correction as follows:

Column 3, line 41, for "spinder" read *spider*; column 4, line 18, for the word "All" read *An*; line 27, for "and arm" read *an arm*;
and that the said Letters Patent should be read with these corrections therein that the same may conform to the record of the case in the Patent Office.

Signed and sealed this 13th day of June, A. D. 1950.
